CLAIM

The ornamental design for a stained glass panel hanger, as shown and described.

DESCRIPTION

FIG. 1 is a front elevation view of a stained glass panel hanger showing my new design, it being understood the rear view is a mirror image thereof;

FIG. 2 is a side elevation view thereof.

The side opposite that shown in FIG. 2 of the drawing is understood to be flat and unornamented.

FIG. 1.

FIG. 2.
